UNITED STATES PATENT OFFICE.

CHARLES LINCOLN LOGAN, OF LOS ANGELES, CALIFORNIA.

FARE-REGISTER.

SPECIFICATION forming part of Letters Patent No. 499,746, dated June 20, 1893.

Application filed September 5, 1892. Serial No. 445,096. (No model.)

To all whom it may concern:

Be it known that I, CHARLES LINCOLN LOGAN, a citizen of the United States, residing at Los Angeles, in the county of Los Angeles and 5 State of California, have invented certain new and useful Improvements in Fare-Registers, of which the following is a specification.

My invention relates to fare registers, and has reference more particularly to that class 10 of registers in which the fares are registered in two different places, one of which shows a continuous account known as the "total number" while the other represents an account for each half-trip. Such fares as are registered by this counter, except the total number, are to be canceled and the trip register 15 set to 00 at the end of each half-trip.

The object of my invention is to provide a sure and absolute check on the conductor; to 20 detect dishonest conductors; to avoid what is known as "jumping;" and finally to provide a register which shall be light and handy when used as a portable device.

To these ends my invention consists in various features, details, and combinations hereinafter set forth and claimed.

In the accompanying drawings,—Figure 1 is a face view, partly in section, of my improved register; Fig. 2, a rear view of the same 30 also partly in section; Fig. 3, a vertical longitudinal sectional view of the same; Fig. 4, a face view of the mechanism for setting the trip counters to 00 and for shifting the trip sign; and Fig. 5, a view illustrating the construction and arrangement of the continuous counter mechanism.

A indicates a box, shell, or casing which is designed to be sealed or otherwise closed against access to the interior by the conductor 40 or other unauthorized persons. Mounted within this box or casing is a frame which supports the operative parts of the mechanism, which frame comprises two plates B and C connected by suitable posts B² as shown in Fig. 3. Secured upon the rear face of the plate C are two guiding ribs or plates D between which works the actuating rod or stem E, as clearly shown in Fig. 2. This rod or stem E is provided at its upper end with an 45 inclined laterally projecting rib a, Figs. 2 and 3, which is designed to cause the ringing of the bell or gong at each downward reciproca-

tion of the rod or stem E. The bell or gong F which is also secured to the rear face of plate C, is provided with a hammer b carried 55 near the end of the spring arm c,—the end of said arm c being arranged in the path of the laterally-projecting portion a of the rod or stem E, as shown in Fig. 2.

When the rod or stem E is pulled downward, the inner edge or face of the rib a thereon will strike against the end of the spring arm c (which end is bent laterally as shown in Fig. 3) and force said arm inward toward the center of the gong or bell. As soon as the 60 rod or stem is carried downward as far as may be necessary to actuate the register, the end of the spring arm will ride off the upper end of the rod or stem, and its elasticity will throw the hammer b against the gong and thereby 65 sound the latter.

When the rod or stem E is raised to its normal position by the spring G, the inwardly-turned end of the spring arm c will ride along the outer face of the rib a and pass off the 70 outer end of the latter and assume the position shown in Fig. 2.

The rod or stem E is provided on one of its side faces with a series of notches or a rack-bar d, Fig. 2, with which is adapted to engage 80 a pawl or dog e pivoted to the rear face of plate C, the pawl or dog being held in its normal position by a light spring f, as indicated by the dotted line in Fig. 2. This pawl or dog is employed for the purpose of locking 85 the rod or stem against movement unless it be carried upward and downward to its full and proper extent. If the rod be pulled part-way out it will have to be pulled the remainder of the distance before it can be returned, 90 as the teeth of the bar d will be engaged by the pawl or dog e; or in case the rod has been partially returned, it must be returned to its full normal position before it can be pulled outward again. In other words, if the rod or 95 stem E be stopped at any intermediate point between the extremes of movement, it will be locked by reason of the pawl e engaging the rack bar d of the rod or stem. The rod or stem E is returned to its normal position, 100 Fig. 2, by means of a coiled spring G fastened at one end to the shell or casing, and at the opposite end to the rod or stem.

H indicates a pawl or dog pivotally secured

to the rear side or face of the rod or stem E, as clearly shown in Fig. 2; the said pawl or dog being adapted to engage a ratchet wheel I (which is provided with ten teeth) secured 5 rigidly upon a shaft J extending from front to rear of the register,—the construction and arrangement being such that every time the rod or stem E is pulled downward it will impart to the ratchet wheel I one-tenth of a rotation.

The shaft J to which I have just referred, carries at its front end on the front side of the plate C, a disk or wheel K which has a single tooth L, Fig. 1, and is further provided 15 on its front face with numerals ranging from 0 to 9 inclusive. There is also mounted upon the shaft J immediately under the disk K, a mutilated gear M which has an extended flat face, as clearly shown in Figs. 3 and 4; the 20 said parts K and M being made fast to the shaft J. Upon the front face of plate C is a second disk or wheel N, which is provided with ten teeth O, adapted to be struck successively by the single tooth L of the disk or 25 wheel K; said disk or wheel N being provided on its front face with numerals corresponding with those on the disk or wheel K, as clearly shown in Fig. 1. The disk or wheel N is secured to the shaft P by means of a screw P', 30 Fig. 1, or in any other suitable manner. Beneath the disk or wheel N, which is fast upon the short shaft P, Fig. 4, is a second mutilated gear wheel Q, as clearly shown in Figs. 3 and 4 which is also fast upon the shaft P.

The shell or casing A is provided with an opening R in its front face through which will be displayed one numeral of each of the wheels or disks K and N,—the numerals on the lower wheel or disk K representing 40 units, while those on the upper disk N represent tens. From this construction it will be seen that every time the rod or stem E is pulled downward its pawl H will engage the ratchet wheel I and give said wheel and its 45 shaft J one-tenth of a rotation, and inasmuch as the lower disk K is also secured rigidly upon the shaft J, it, the said disk K, will turn or rotate one-tenth of a rotation at the same time. Every time that the lower wheel or disk

50 K is thus given one-tenth of a rotation it will display a new number through the opening R. When this wheel or disk K has made one complete rotation, its single tooth L will strike one of the teeth O of the upper disk or wheel 55 N and turn or rotate said upper disk or wheel one-tenth of a rotation, and thereby cause a new number to be displayed through the opening R. These two disks or wheels K and N are provided with numbers sufficient to 60 register one hundred fares, which is all that would be ordinarily required on a half-trip; but should it be found desirable to provide for a further or greater registration of fares, an additional wheel or disk could be employed which should indicate the number of 65 hundreds.

The total register is constructed as follows:

Projecting from the shaft J is a radial arm S in which is pivoted a spring-actuated pawl or dog g which is adapted to engage a ratchet wheel T mounted loosely upon the shaft J as shown in Figs. 2, 3, and 5. This ratchet wheel T is secured to or forms part of a disk U which is provided with a single tooth or projection h on its periphery and with a series of numbers from 0 to 9 on its rear face, the numbers being displayed through a suitable opening V formed in the rear face of the shell or casing A, as shown in Fig. 2. The disk U which carries the ratchet wheel T, being mounted 70 loosely upon the shaft J, is given a one-tenth rotation at each downward pull of the rod E, by reason of the engagement of the pawl g with the said wheel T; it being understood, of course, that the arm S carrying the pawl is 75 fast to the shaft J and turns or rotates therewith as the dial K is rotated by the rod E. The rotation of the wheel or the disk U, which is the units dial of the total register, effects the rotation of the remaining dials of such register in the manner now to be explained. Directly above the disk U are the wheels W, X, and Y, each having numerals from 0 to 9 on their rear faces, as plainly indicated in Fig. 80 85 90 95 100 105 110 115 120 125 130 135 140 145 150 155 160 Fig. 3, which engaging the teeth of said ratchet wheel, holds the latter against turning and, prevents the actuation of this train of gearing when the trip counters K and N are being set to 00.

From the foregoing description it will be seen that every time the rod or stem E is pulled downward to actuate the trip registers, the lower disk or wheel U of the total register will be at the same time turned or rotated to correspond, and as the resetting of the trip register disks K and N does not affect the total register, the latter will at all times show the total number of fares that have been registered. In order to reset the trip register at the end of each half-trip and to change the direction or trip signal device, I employ the mechanism illustrated in Figs. 1 and 4.

Mounted upon the front face of plate C is a plate or slide n whose inner end is bifurcated to receive an elongated lug or projection o secured rigidly upon plate C; the lug serving to guide the slide in its movements into and out of the shell or casing A, which latter is slotted at one end to receive the slide. This lug or projection o, which remains fixed relatively to the slide, is provided with a rack bar p with which it is designed to engage a spring-actuated pawl q, the construction and arrangement being such that if the slide be pulled part way out it will have to be pulled the remainder of the distance before it can be returned; or in case it has been partially returned, it must be returned to its full normal position before it can be pulled outward again. The slide is further provided with a pointed projection r which is designed to engage a pointed dog s pivoted in a plate t, which latter is adapted to reciprocate at right angles to the slide n over which it is placed, as clearly shown in Fig. 4. The plate t is guided in its movements by suitable ways u, and is reciprocated by means of a pin or stud v working in a double cam groove w, x in the back of the plate t, as shown in Fig. 4. This plate t is provided with posts or supports y which carry the direction plate z, having the words "in" and "out" shown in Figs. 1 and 4. The actuating slide n is provided in its upper and lower edges with teeth a' which, under certain conditions, are adapted to engage the teeth of the mutilated gears M and Q of the trip counter wheels. These mutilated gears are so disposed with reference to the numbers of figures contained on the disks K and N as that when the latter are at 00 the flat faces of the gears will be parallel with the upper and lower edges of the actuating slide n, so that in case said slide should be pulled outward, it would ride past these flat faces without engaging or actuating the gears. If, however, the rod or stem E has been previously pulled down one or more times the gears will have been turned and their teeth brought into line with the teeth a' on the plate n so that in case it be attempted to pull the slide n outward, such movement

will effect a rotation (to the right) of the lower gear wheel M and the disk or wheel K connected therewith.

If the register has been operated a sufficient number of times to cause the tens wheel or disk N to turn one-tenth of a rotation or more, the teeth of the upper gear wheel Q will also be thrown into the path of the teeth a' on the upper edge of the slide n, so that when the slide is moved outward it will effect a rotation of the gear wheel Q and of the tens disk or wheel N. In other words, unless both disks be set at 00 an outward movement of the slide n will effect a rotation or turning of such disk. It is important to observe that when these disks are turned or rotated by means of the rod or stem E and the intermediate connections, the lower gear M will turn to the left and the upper gear Q will turn to the right; but when the slide n is pulled outward and it engages these gears, it reverses this movement of the latter and causes the lower gear to revolve to the right and the upper gear to the left. It will be seen from this construction that the slide n and the rod or stem E cannot both be actuated at the same time as these gear wheels M and Q are fast upon their shafts.

If the slide n should be pulled out only part way and the rod or stem E be pulled downward, the latter can be pulled only part way, as the teeth of the gear M being in engagement with the teeth a' of the slide n will not permit the wheel to revolve to the left, as it must do when actuated by the rod or stem. So too, if the slide n be pulled out only part way, and the rod or stem E also be pulled down part way, it will be seen that neither one could be moved farther, as the rod or stem E could not be returned to place while held by its locking pawl e and rack d, while the slide n could not be returned because of the engagement of the dog q with the rack p.

In order to set the trip register at 00 it is only necessary to pull the slide n outward so that in case any fares have been registered, the teeth a' of the slide may turn or rotate the shafts J and P and their gears M and Q so as to bring the flat face of the mutilated gears parallel to the upper and lower edges of the slide, when of course there is nothing to prevent, so far as the resetting is concerned, the inward movement of the slide.

When the parts are in the position shown in Figs. 1 and 4 the plate t is in its lowermost position, and the slide n is in its normal position within the case. If the slide be now pulled outward, the pin or stud v, riding along the inclined portion w of the cam slot, will cause said plate t to move upward until the said pin or stud arrives at the apex of the cam slot, when it will ride out of the latter. At about the time that the pin v or stud rides out of the cam slot w, the pointed projection r on the plate n will strike the under side of the pivoted dog s of the plate t and cause a further slight upward movement of

the plate. This upward movement of the plate *t* is given to insure the entrance of the stud or pin *v* into the lower portion *x* of the cam slot, so that when the slide is pushed inward 5 again it will, riding in the inclined portion *x* of the slot, cause the plate *t* (carrying the direction plate *e*) to rise still higher and display through a suitable opening *b'* in the front of the case *A*, the word "in" in lieu of 10 the word "out" which was previously displayed through such opening. As the plate *t* is thus carried upward, the nose of the dog *s* will strike the lower edge of one of the ways or guides *u*, and the point or nose of 15 such dog will be thrown below its center so that the next time that the pointed projection *r* on the plate *n* comes in contact with the dog, it will ride upon the upper face of the latter and give the plate *t* a slight downward movement instead of a slight upward movement as it did under the previous adjustment. 20

If the word "in" is opposite the opening *b'*, and it is desired to change it so as to display 25 the word "out," it is only necessary to pull the slide *n* outward, and return it to its normal position. The pin *v*, working in the lower part of the slot *x* carries the plate *t* downward until the pin shall have moved out 30 of the slot *x*. The pointed projection *r* comes into contact with the upper face of the pivoted dog and gives the plate *t* a slight downward movement so as to insure the entrance of the pin or stud into the upper part *w* of 35 the slot *wx*. It will thus be seen that by the movement of a single plate or slide as *n*, I effect not only a resetting of the trip counter but also effect a change in the direction plate. 40

The particular register shown in the drawings is designed to be carried by the conductor, and as it weighs but nine ounces, it cannot be considered injurious to the health of the conductor as has been contended concerning other registers. It is to be understood, however, that the invention is not restricted to portable registers, as it is clearly adapted to be secured in position within a vehicle in the same manner as other registers now in use. 45

An important advantage in the present construction resides in the fact that the register cannot "jump" as frequently occurs with other registers which I have seen in operation. A register which is known to jump 50 once, is thereafter not to be relied upon as a check upon the conductor, for if he chooses to pocket a certain number of fares, he has but to claim that his register jumped. By placing both units-dials upon the same shaft 55 and causing them to rotate in unison; and by making a simple and direct acting dial-actuating mechanism, I avoid all possibility of the jumping of the register. 60

As a general rule, fare registers are beaten 65 by the operation of the trip-indicator sign; but under my construction any attempt to beat the register by the actuation of the trip-sign

will result in sure detection, as the conductor could neither ring the bell nor register a fare. 70

Having thus described my invention, what I claim is—

1. In a fare register, the combination with a casing; of two independent shafts *J* and *P* carrying, respectively, the units and tens trip-dials *K* and *N*; the single tooth wheel *L* mounted upon shaft *J*; the ten tooth wheel *O* mounted upon shaft *P* and adapted to be engaged by wheel *L*; the total-register unit-dial *U* mounted loosely upon the shaft *J*; a ratchet wheel *T* secured to the dial *U*; an arm *S* secured to the shaft *J* and provided with a pawl *g* to engage the ratchet wheel; means for resetting the trip-dials; and a detent for holding the unit-dial *U* at rest during the resetting operation. 75

2. In a fare register, the combination with the trip-dials *K* and *N*, and their mutilated gears, of means for turning them in one direction, and a resetting means adapted to engage the gears and turn them in the opposite direction. 80

3. In a fare register, the combination with the trip dials *K* and *N*, and their mutilated gears, of the actuating rod or stem adapted to turn them always in one direction, and a sliding toothed plate, adapted to turn them in the opposite direction. 95

4. In a fare register, the combination with the trip-dials *K* and *N*, of the mutilated gears having their inactive faces in line with the 0 on the respective dials, means for rotating each dial always in a given direction, and a toothed plate working between the gears. 100

5. In a fare register, the combination with the trip dials *K* and *N* and their actuating mechanism, of a slide *n*, and means substantially such as shown and described for re-setting the dials, so disposed with reference to the actuating mechanism that the re-setting and the actuation of the dials cannot be effected at the same time. 105

6. In a fare register, the combination with the trip dials *K* and *N* and their actuating mechanism, of a slide *n*, and suitable connections for re-setting the dials,—said resetting means being normally inert and adapted to come into play only in case the dials have been operated by their actuating mechanism, all substantially as shown and described. 110

7. In combination with the trip dials *K* and *N*; a resetting slide for the latter; and an actuating mechanism for said dials arranged in such relation to the re-setting slide as to be incapable of action during the operation of the re-setting slide, all substantially as shown and described. 115

8. In a fare register, the combination with the trip dials *K* and *N*, of a sliding plate *n* and intermediate connections for setting the dials, and a trip-indicating plate actuated by said slide. 120

9. In a fare register, the combination with the trip dials *K* and *N*, of a sliding setting plate

therefor provided with a pin or stud v , and the indicator plate t provided with the cam slot $w\ x$.

10. In a fare register, the combination with 5 the indicator plate t , provided with a V-shaped cam slot $w\ x$; of a slide n provided with a pin v ; a projection r upon the slide, and a pivoted dog s mounted upon the plate in position to be struck by the projection r .

11. In a fare register, the combination with 10 the plate t provided with a V-shaped cam-

slot, and with a pivoted dog s of means for rocking the dog, and the slide n provided with a pin v to enter the cam slot, and with a projection r to engage the dog.

In witness whereof I hereunto set my hand 15 in the presence of two witnesses.

CHARLES LINCOLN LOGAN.
